(57) **CLAIM**

The ornamental design for a cable gland, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is an isometric view of a front, top, and right side of an ornamental design for a cable gland;

FIG. 2 is a left side elevational view of the cable gland of FIG. 1;

FIG. 3 is a right side elevational view of the cable gland of FIG. 1;

FIG. 4 is a top plan view of the cable gland of FIG. 1;

FIG. 5 is a bottom plan view of the cable gland of FIG. 1; FIG. 6 is a front elevational view of the cable gland of FIG. 1;

FIG. 7 is an isometric view of a front, top, and right side of another ornamental design for a cable gland;

FIG. 8 is a left side elevational view of the cable gland of FIG. 7;

FIG. 9 is a right side elevational view of the cable gland of FIG. 7;

FIG. 10 is a top plan view of the cable gland of FIG. 7;

FIG. 11 is a bottom plan view of the cable gland of FIG. 7; FIG. 12 is a front elevational view of the cable gland of FIG. 7;

FIG. 13 is an isometric view of a front, top, and right side of yet another ornamental design for a cable gland;

FIG. 14 is a left side elevational view of the cable gland of FIG. 13;

FIG. 15 is a right side elevational view of the cable gland of FIG. 13;

FIG. 16 is a top plan view of the cable gland of FIG. 13;

FIG. 17 is a bottom plan view of the cable gland of FIG. 13; FIG. 18 is a front elevational view of the cable gland of FIG. 13;

FIG. 19 is an isometric view of a front, top, and right side of still another ornamental design for a cable gland;

FIG. 20 is a left side elevational view of the cable gland of FIG. 19;

FIG. 21 is a right side elevational view of the cable gland of FIG. 19;

FIG. 22 is a top plan view of the cable gland of FIG. 19;

(Continued)

FIG. 23 is a bottom plan view of the cable gland of FIG. 19; (56)

and,

FIG. 24 is a front elevational view of the cable gland of FIG. 19.

The dash-dash-dash broken lines are included for the purpose of illustrating portions that form no part of the claimed design. The yellow color shown in FIGS. 1, 6, 7, 12, 13, 18, 19, and 24 forms a part of the claimed design.
